UNITED STATES PATENT OFFICE.

DAVID COCKBURN AND DONALD MACNICOLL, OF CARDONALD, NEAR GLASGOW,
SCOTLAND.

SAFETY-VALVE.

1,169,926.

Specification of Letters Patent.

Patented Feb. 1, 1916.

Application filed August 14, 1914. Serial No. 856,823.

To all whom it may concern:

Be it known that we, DAVID COCKBURN and DONALD MACNICOLL, subjects of the King of the United Kingdom of Great Britain and Ireland, and residents of Cardonald, near Glasgow, Scotland, have invented a certain new and useful Improvement in Safety-Valves, of which the following is a specification.

10 This invention relates to safety valves of the type including a main valve and a pilot valve, the opening of which pilot valve, under normal conditions, results in the automatic opening of the main valve.

15 Now, the present invention provides means whereby the main valve may be opened positively without altering the position of the pilot valve.

In the accompanying drawing Figure 1 is 20 a side elevation. Fig. 2 a plan of a safety valve embodying the invention. Fig. 3 is a vertical section drawn through the valve. Fig. 4 is a side elevation of the valve on a reduced scale from that shown in the remaining figures of the drawings. Fig. 5 is 25 an irregular horizontal section drawn on the line *a—a* of Fig. 3. Fig. 6 is a vertical transverse section drawn on the irregular line *b—b* of Fig. 5.

30 Referring to the drawing, 1 denotes the spindle of the pilot valve 1' which serves under normal conditions to control the main valve 2, said valve spindle 1 receiving actuation from a lever 3 fulcrumed on the valve 35 casing at 4 and coöperating with a cam element 5 keyed to a rock shaft 6 on which shaft 6 is a tappet arm 7 arranged in operative relationship with the main valve. On initial movement of the shaft 6 the cam element 5 engages the coöperating arm of the 40 said lever 3 and acts to tilt said lever so that the end 8 of the short arm of said lever engages a shoulder 9 on the spindle 1 of the pilot valve and thereby opens said pilot valve. Under normal conditions, when the 45 pilot valve is opened, the main valve opens automatically under the influence of steam pressure controlled by said pilot valve; if, however, the main valve fail to open automatically either by reason of the absence of

steam pressure or as a result of adhesion of the main valve stem to its guide, then, on continued movement of the shaft 6, the tappet arm 7 engages the main valve 2 and opens the same positively. As will be evident from the drawing, the cam element 5 in participating in the further movement of the shaft 6 does not affect the coöperating lever 3, the position of the pilot valve being thereby unaltered.

The rock shaft 6 is provided at one end with a crank arm 10 to the free end of which is pivoted one end of a connecting rod 11 extending to within convenient reach of the operator.

Having now described our invention what we claim and desire to secure by Letters Patent of the United States is:—

1. In a safety valve, in combination, a main valve, a separate pilot valve normally adapted when open to effect the automatic opening of said main valve, and manually operable means including a rock-shaft adapted in the first part of the rocking movement thereof to effect the positive opening of said pilot valve and thereafter on further movement of said shaft to effect the positive opening of said main valve without further displacement of said pilot valve.

2. In a safety valve, in combination, a main valve, a pilot valve adapted when open to effect the automatic opening of said main valve, and a train of connections for effecting successively the positive opening of said pilot valve and of said main valve, said train of connections including an interponent which when moved into one position acts to open the pilot valve, and when moved to a position at which the main valve is opened acts to maintain the pilot valve in open position so that any movement of the main valve effected by action of the pilot valve or by the train of connections has no effect on the pilot valve.

3. In a safety valve, a pilot valve, a main valve, means including a cam element and a coöperating lever for transmitting movement to said pilot valve, and a tappet arm adapted for direct coöperation with the main valve, said cam element and lever and

said tappet arm being adapted to act successively, said tappet arm acting on the main valve after the action of the cam element and lever on the pilot valve, and only in case of failure of the main valve to open automatically.

In testimony whereof we have signed our

names to this specification in the presence of two subscribing witnesses.

DAVID COCKBURN.
DONALD MACNICOLL.
